(57) **CLAIM**

The ornamental design for a confectionery product, as shown and described.

DESCRIPTION

FIG. 1 is a perspective view of the confectionery product having a generally square configuration with rounded corners and generally circular indentations in top and bottom sides thereof;

FIG. 2 is a top plan view of the confectionery product illustrated in FIG. 1, showing the indentation in the top side thereof, the bottom side thereof being a mirror image of the top side shown in FIG. 2;

FIG. 3 is a side elevation view of the confectionery product illustrated in FIGS. 1 and 2, the other three sides thereof being a mirror image of the side shown in FIG. 3; and, FIG. 4 is a cross-sectional view of the confectionery product illustrated in FIGS. 1 through 3, showing the indentations in the top and bottom sides thereof.

A characteristics feature of the design resides in the shape and configuration of the article and/or the pattern and ornament applied to the article as shown in the representations, the article being transparent and the star-shaped representing particles of opaque material, which are arranged throughout the article in a random fashion.
